(57) **CLAIM**

The ornamental design for a frequency-steered sonar transducer assembly, as shown and described.

DESCRIPTION

FIG. 1 is a right top perspective view of a frequency-steered sonar transducer assembly in accordance with an embodiment of the present invention;

FIG. 2 is a front view of the frequency-steered sonar transducer assembly of FIG. 1;

FIG. 3 is a rear view of the frequency-steered sonar transducer assembly of FIG. 1;

FIG. 4 is a right view of the frequency-steered sonar transducer assembly of FIG. 1;

FIG. 5 is a left view of the frequency-steered sonar transducer assembly of FIG. 1;

FIG. 6 is a top view of the frequency-steered sonar transducer assembly of FIG. 1;

FIG. 7 is a bottom view of the frequency-steered sonar transducer assembly of FIG. 1;

FIG. 8 is a right top perspective view of a frequency-steered sonar transducer assembly in accordance with another embodiment of the present invention;

FIG. 9 is a front view of the frequency-steered sonar transducer assembly of FIG. 8;

FIG. 10 is a rear view of the frequency-steered sonar transducer assembly of FIG. 8;

FIG. 11 is a right view of the frequency-steered sonar transducer assembly of FIG. 8;

FIG. 12 is a left view of the frequency-steered sonar transducer assembly of FIG. 8;

FIG. 13 is a top view of the frequency-steered sonar transducer assembly of FIG. 8; and,

FIG. 14 is a bottom view of the frequency-steered sonar transducer assembly of FIG. 8.
